Moffatt E. Finck, Burlington, Iowa, assignor to
Murray Iron Works Company, Burlington,
Iowa, a corporation of Iowa

Application August 6, 1932, Serial No. 627,720

3 Claims. (Cl. 122—331)

This invention relates to boilers incorporating a down draft furnace.

The primary object of my invention is to provide highly efficient combustion of the fuel and 5 to reduce the stack temperatures to a minimum.

Other objects are to so support the fuel that the volatile matter therein may be burned before passage of the fuel to the fire bed; to support the fuel by a part of the water circulating system 10 of the boiler so that the high temperature adjacent the fire bed may be utilized in heating the water; to utilize the wall temperatures of the boiler in the heating of the water; and to provide a boiler of simple and economical construction 15 and efficient and thorough operation.

In the selected embodiment of the invention illustrated in the accompanying drawings

Fig. 1 is a front elevation of a boiler embodying my invention;

20 Fig. 2 is a side elevation;

Fig. 3 is a vertical transverse section taken substantially on the line 3—3 of Fig. 2; and

Fig. 4 is a vertical longitudinal section taken substantially on the line 4—4 of Fig. 1.

25 The boiler includes a shell 5. A refractory lining 6 is provided within the shell and suitable insulation 7 is interposed between the shell and lining to retain the heat in the boiler and increase the efficiency thereof. A steam drum 8, made of 30 steel plate riveted or welded together or a casting, is provided at the forward upper end of the boiler and at the lower rear end of the boiler is a water drum 9, similar in construction to the drum 8, and to which the usual water inlet 10 is connected. A plurality of bent boiler tubes 11 interconnect the drums 8 and 9 and the bent tubes are placed and baffled to be in direct contact with the products of combustion and are designed to 35 set up a rapid roundabout circulation of the water. The disposition of the tubes is such that substantially all of the heat is extracted from the products of combustion passing thereover whereby the stack temperature is reduced. I have found that this can best be accomplished by 40 arranging the tubes in banks and in the present instance the tubes are disposed in horizontal banks. Moreover, greater efficiency is attained in boiler operation if the area of the hot gas 45 passages is maintained substantially constant.

50 Furthermore, there is a certain amount of radiated heat from the fire on the grate in the boiler and it is advantageous to utilize this heat in the heating of the tubes. Furthermore, the efficiency of the boiler is increased by passing the 55 heated gases over the tubes more than one time

and to obtain this double pass effect and increase the effectiveness of the radiated heat I provide a baffle in the boiler which is disposed behind the lowermost bank of tubes and at the free end of this baffle I provide a flange which projects toward the opposite wall of the boiler. The baffle and the flange thereon are terminated in spaced relation with other parts of the boiler so that gas passages of substantially uniform size are provided and the uniformity of size of the gas 60 passages may also be maintained by providing a bridge wall behind the grate and beveling this bridge wall in a proper manner. The boiler includes a down draft furnace and, when coal or other solid matter is used, it burns on the usual 65 rocking grate 12 having the customary ash pit 13 therebelow to which access may be had through the door 14, a fire door 15 being provided above the grate for the purpose well understood. The draft and loading door 16 is arranged above the 70 fire door 15 below the draft tube 17 having the damper 18 therein. A small water drum or header 19 is provided adjacent the front wall of the boiler intermediate the doors 15 and 16. Another small water drum or header 20 is provided 75 in the furnace inwardly of and in a horizontal plane above the horizontal plane of the drum 19. The drums 19 and 20 are connected by a plurality of spaced apart forwardly inclined tubes 21 providing a grate above the rocking grate 12. The 80 drum 20 is connected with the drum 8 through tubes 22 and the drum 19 is connected with the drum 8 through tubes 23. The drum 19 is also connected with the drum 9 through tubes 24 as will be explained more fully hereinafter. The 85 interconnection of the drums 19 and 20 with the drums 8 and 9 insures circulation of water through the tubes 21 and these tubes are arranged to provide what I call a water grate. The tubes 21 are disposed immediately above the fire bed 90 supported on the rocking grate 12 and are therefore subjected to intense heat. Solid fuel, such as coal, is introduced into the furnace through the door 16 and is supported on the water grate provided by the tubes 21. This fuel falls from 95 the tubes 21 onto the fire bed or grate 12 and as the fuel burns the draft draws volatile matter from the coal or the like on the water grate down into contact with the fire on the lower grate where the volatile matter is consumed. This 100 insures greater efficiency and practically smokeless combustion. It is obvious that during the operation of the boiler the refractory lining 6 is intensely heated. This lining is materially thickened adjacent the grates 21 and 12 in the portion 105 110

constituting the fire box of the boiler and this added or thickened portion of the refractory lining is indicated by 25. The tubes 24 and tubes 26, which extend between the drums 8 and 9, 5 are embedded in the thickened lining 25 and water circulating through the tubes 24 and 26 is heated by the heat absorbed by the lining 25 so as to utilize the heat of the lining. Heat from fuel burning on the grate 12 passes up over the 10 water grate 21 and then flows along the underside of the baffle thereby heating the lowermost bank of tubes and this heat subsequently passes through the opening between the water drum 9 and the flange on the baffle and flows over the 15 other banks of tubes and heats them, and it is therefore obvious that the heat flows in two directions over the banks of tubes thereby giving a double pass effect.

The boiler is provided with the usual appurtenances such as water and pressure gages, grate shaking devices and tube cleaning facilities but, 20 as the particular construction of these parts constitutes no particular part of my invention, specific reference thereto is not made.

25 In the foregoing description I have described a boiler adapted to be fired with a solid fuel such as coal but my invention is not limited to use with such a boiler for it may be used with an oil or gas fired boiler. Under such circumstances, the 30 tubes 21 do not serve as a grate but are nevertheless advantageous since they absorb heat immediately above the burner for the oil or gas, which burner will be positioned somewhat similarly to the grate 12. It is also to be understood 35 that the invention and the parts and construction are susceptible of variation and modification within the spirit and scope of the following claims.

I claim:

40 1. In a boiler, spaced drums, a bank of tubes interconnecting said drums, a baffle arranged behind the lowermost row of tubes, heating means, and means directly interconnected with the drums and including tubes arranged immediately 45 above said heating means to be subjected to the heat of said heating means whereby heat flowing from the heating means flows over the second-named tubes and along the underside of the

baffle to heat the lowermost row of tubes and subsequently flows over the other rows of tubes to heat the same.

2. In a boiler, water and steam drums, a bank of tubes interconnecting said drums and arranged in 80 rows, a baffle behind the lowermost row of tubes, a grate, a pair of headers above said grate and interconnected by a plurality of spaced apart tubes and providing a support above the grate for fuel to be passed thereto, means directly interconnecting the headers and the plurality of spaced apart tubes with the water and steam drums, said 85 grate being disposed so that heat from fuel burned thereon flows over said plurality of spaced apart tubes and then along the underside of said baffle to heat the lowermost row of tubes and then over the other rows of tubes to heat the same.

3. In a boiler, a grate, a steam drum mounted at the upper front end of the boiler, a water drum mounted at the lower rear end of the boiler, a plurality of bent boiler tubes interconnecting said drums and arranged in banks, a baffle behind the lowermost bank of tubes, a water header adjacent the front wall of the boiler intermediate 100 the baffle and the grate, tubes directly connecting said header with said water and steam drums, another water header in the boiler inwardly of the first header and in a horizontal plane above the horizontal plane of the first header, tubes 105 interconnecting this header and the steam drum, a plurality of spaced apart forwardly inclined tubes interconnecting said headers and adapted to be filled with water and extending above said grate whereby fuel introduced into said boiler 110 is supported by the forwardly inclined tubes, the volatile matter from the fuel supported on said forwardly inclined tubes being drawn into contact with the burning fuel on the grate where it is consumed to thereby increase the efficiency 115 of burning of the fuel, the products of combustion from fuel burned on said grate passing over said forwardly inclined tubes to heat the same and along the underside of said baffle to heat the tubes in the lowermost bank and then over the 120 other banks of tubes to thereby heat the same.
